UNITED STATES PATENT OFFICE.

MARSHALL J. PALMATIER, OF GLOBE, ARIZONA.

CARBURETER.

Specification of Letters Patent. Patented June 25, 1918.

1,270,547.

Application filed July 20, 1917. Serial No. 161,765.

To all whom it may concern:

Be it known that I, MARSHALL J. PALMATIER, a citizen of the United States, residing at Globe, in the county of Gila, State of Arizona, have invented certain new and useful Improvements in Carbureters; and I do hereby declare the following to be a full, clear, and exact description of the invention, such as will enable others skilled in the art to which it appertains to make and use the same.

This invention is an improvement in internal combustion engines and has particular reference to a carbureter therefor.

An object of the invention is to provide an improved carbureter wherein the mixture is heated in a novel manner whereby a more powerful explosion will be produced in the cylinders than heretofore by causing the fuel to burn more slowly and thus carry out the full length of the combustion stroke. This slow burning of the fuel eliminates the usual "knock" explosion which rapidly deteriorates the bearings, differential, and transmission and also prevents the accumulation of carbon.

The inventive idea involved is capable of receiving a variety of mechanical expressions, one of which, for the purpose of illustrating the invention, is shown in the accompanying drawings, wherein:

Figure 1 is a top plan view of the exhaust manifold of an engine showing the carbureter applied thereto.

Fig. 2 is a front elevation thereof with the carbureter in vertical section.

Fig. 3 is a side elevation thereof.

Fig. 4 is a section on the line 4-4 of Fig. 2.

Fig. 5 is an enlarged fragmentary section through the mixing chamber of the carbureter.

Fig. 6 is a section on the line 6-6 of Fig. 1.

Fig. 7 is an enlarged fragmentary transverse section through the intake manifold showing the connections between the same and the float chamber of the carbureter.

Fig. 8 is a sectional view through a valve controlling device employed in connection with the invention.

Fig. 9 is an elevation thereof.

The carbureter is shown in the accompanying drawings in what is now believed to be its preferred form and is constructed for

use in mixing gasoline, naphtha, coal oil, or other fuel.

The combustion engine is conventionally illustrated by the numeral 15 and is provided with the exhaust manifold 16 and the intake manifold 17 both of which are provided with jackets 18 and 19 respectively, for a purpose which will appear in the course of the description. The carbureter is generally indicated by the numeral 20 and is incased by a hot water jacket 21 having an inlet opening 22 for connecting to the engine. A pipe connection 23 is established between the chamber formed by the jacket 18 of the exhaust manifold and the carbureter 20 for conveying hot air from said chamber, which is supplied thereto from the engine, to the mixing chamber 24 of said carbureter and said connection 23 is also provided with a hot water jacket 25 provided at a point adjacent the exhaust manifold with an overflow pipe 26 which leads in any convenient manner to the engine. The hot water chamber formed by the jacket 21 of the carbureter communicates at 27 with the hot water jacket 25 so that it will be seen that the hot water entering the jacket 21 through the inlet 22 will circulate about the carbureter, through the jacket 25 and from thence back into the engine.

The passage of hot air from the chamber around the manifold 16 through the connection 23 and into the mixing chamber 24 is preferably controlled by a valve 28 carried by the stem 29 which extends upwardly into a casing 30 in which is mounted a coil spring 31 surrounding said stem and the tension of which is regulated by the regular nuts 32 whereby the pressure upon the valve 28 may be varied. There is provided in the bottom of the carbureter an outlet pipe 32' for the hot water chamber formed by the jacket 21 and a similar pipe 33 for the intake manifold 17. This manifold is further provided with an outlet 34 for the purpose of saving fuel when allowing the engine to run on compression.

The float chamber 35 is provided with the usual oil inlet 36 and has pivotally mounted therein at 37 a bracket 38 to one end of which is secured the float 39, the other end of said bracket having the usual check valve 40 for controlling the passage of fuel into the float chamber. In order to heat the fuel in said chamber there is preferably extend-

ing therethrough an electric coil 41 which is only employed when starting the engine in cold weather. The float chamber 35 is provided with a normally closed drain outlet 42. The flow of fuel from the float chamber 35 to the mixing chamber 24 is regulated by a needle valve 43 controlled by a device 44 which will later be described in detail, and the mixing chamber 24 has mounted therein the pipe 45 which communicates with the float chamber and carries the usual Venturi tube or nozzle 46 employed for spraying the fuel into said mixing chamber. This mixing chamber is further provided with a butterfly valve 47 carried by the shaft 48 which is controlled by the lever 49.

It will be understood that a certain amount of vapor is formed in the float chamber 35 by reason of the hot water in the jacket 21 and in order to feed this vapor into the intake manifold and thus provide a regular flow of fuel to the Venturi tube 46 whereby the back pressure on the intake valve 28 will be prevented, there is preferably provided a curved pipe 50 one end of which is mounted in the cover of the float chamber 35 while the other end extends into the manifold 17 at 51. The feeding of this vapor from the float chamber into the intake manifold also aids in causing the burning of all of the fuel, thus effecting a saving thereof. The portion of the hot water jacket 21 which is arranged about the float chamber 35 is connected to the jacket 19 by means of a pipe 52.

The hot air chamber formed by the jacket 18 of the exhaust manifold is preferably supplied with air through an intake valve 53 having a number of openings 54, the size of which is controlled by a rotatable ring or cap 55 also having openings 56 adapted to cover and uncover the openings 54 whereby air may enter said chamber and cause the circulation of hot air therein.

The top of the jacket 18 is further provided with a water dripping device generally indicated by the numeral 57, and which will presently be described in detail, having a connection 58 leading to a suitable source of supply and adapted to control a flow of water into the jacket 18 and onto the manifold 16. The contact of the water with the manifold will generate steam which will accumulate in a steam chamber 59 formed by a semi-circular baffle plate or partition 60 which is arranged adjacent the point where the connection 23 enters the jacket 18. This baffle plate 60 will prevent the entrance of steam into the connection 23 and from thence into the carburetor which would otherwise result in too much moisture entering the combustible mixture, but said steam in the chamber 59 will become dry and the vapor therefrom will pass over the partition

and into the connection 23. It will be apparent from the foregoing description that the provision of the several jackets about the different parts will result in a thorough heating of the mixture before entering the engine cylinders and that the mixture in the intake manifold will be made sufficiently moist to properly enrich the same, and also that a complete and slow burning of the fuel will be accomplished, whereby an increase of power will be attained in the combustion stroke of the engine cylinders.

The lever 49 and the controlling devices 44 and 57 are preferably operated simultaneously through any suitable connections, (not shown) to a point adjacent the driver's seat and said devices 44 and 57 are similarly constructed, as shown in Figs. 8 and 9, each comprising a body portion 61 having a recess or chamber 62 therein in which is slidably mounted the needle valve 63 for controlling the passage of a liquid through the valve seat 64, said valve 63 being normally forced downward by means of a coil spring 65. Extending transversely of the top of the body portion 61 and connected to the upper end of the needle valve is a valve actuating arm 66 having a roller 67 upon one end adapted to be engaged by an adjustable segmental plate 68 to which is secured one of the connections for operating the device. It will be apparent from this construction that as the plate 68 is adjusted about its pivot by the connection the same will raise and lower the arm 66 and consequently the needle valve 63 thereby regulating the valve of the liquid through the opening or valve seat 69.

What is claimed is:—

1. In an internal combustion engine, the combination with an exhaust manifold having a hot air jacket, an intake manifold having a hot water jacket, a carburetor having a hot water jacket, a hot air connection between the jacket of the exhaust manifold and the mixing chamber of said carburetor, and a hot water jacket for said connection communicating with the hot water jacket of said carburetor.

2. In an internal combustion engine, the combination with an exhaust manifold having a hot air jacket, an intake manifold having a hot water jacket, a carburetor having a hot water jacket, a hot air connection between the jacket of the exhaust manifold and the mixing chamber of said carburetor, a hot water jacket for said connection communicating with the hot water jacket of said carburetor, and a vapor pipe connecting the float chamber of the carburetor with the intake manifold.

3. In an internal combustion engine, the combination with an exhaust manifold having a hot air jacket, an intake manifold having a hot water jacket, a carburetor having

a hot water jacket, a hot air connection between the jacket of the exhaust manifold and the mixing chamber of said carbureter, a hot water jacket for said connection communicating with the hot water jacket of said carbureter, a vapor pipe connecting the float chamber of the carbureter with the intake manifold, and an overflow pipe connecting the jackets of the carbureter and intake manifold.

4. In an internal combustion engine, the combination with an exhaust manifold having a hot air jacket, an intake manifold having a hot water jacket, a carbureter having a hot water jacket, a hot air connection between the jacket of the exhaust manifold and the mixing chamber of said carbureter, a hot water jacket for said connection communicating with the hot water jacket of said carbureter, and means for feeding water to the jacket of the exhaust manifold to generate steam.

5. In an internal combustion engine, the combination with an exhaust manifold having a hot air jacket, an intake manifold having a hot water jacket, a carbureter having a hot water jacket, a hot air connection between the jacket of the exhaust manifold and the mixing chamber of said carbureter, a hot water jacket for said connection communicating with the hot water jacket of said carbureter, means for feeding water to the jacket of the exhaust manifold to generate steam, and a baffle plate in the hot air jacket

of the exhaust manifold forming a steam chamber therein and arranged adjacent said hot air connection whereby to permit of only the vapor from the steam entering said connection.

6. In an internal combustion engine, the combination with an exhaust manifold having a hot air jacket, an intake manifold having a hot water jacket, a carbureter having a hot water jacket, a hot air connection between the jacket of the exhaust manifold and the mixing chamber of said carbureter, a hot water jacket for said connection communicating with the hot water jacket of said carbureter, and a heating coil in the float chamber of the carbureter.

7. In an internal combustion engine, the combination with an exhaust manifold having a hot air jacket, an intake manifold having a hot water jacket, a carbureter having a hot water jacket, a hot air connection between the jacket of the exhaust manifold and the mixing chamber of said carbureter, a hot water jacket for said connection communicating with the hot water jacket of said carbureter, and an air inlet valve for controlling the admission of air into the hot air jacket of said exhaust manifold.

In testimony whereof, I affix my signature in the presence of two witnesses.

MARSHALL J. PALMATIER.
